UNITED STATES PATENT OFFICE.

GEORGE M. HATHAWAY, OF NEW YORK, ASSIGNOR OF A PART TO DAVID P. DEY, OF BROOKLYN, JEFFERSON T. RAPLEE AND WARREN S. DEY, OF NEW YORK, AND JOHN L. HUBBARD, OF NEW ROCHELLE, N. Y.

PERMUTATION-LOCK.

SPECIFICATION forming part of Letters Patent No. 248,173, dated October 11, 1881.

Application filed September 19, 1881. (Model.)

To all whom it may concern:

Be it known that I, GEORGE M. HATHAWAY, a citizen of the United States, residing at New York, in the county of New York and State of New York, have invented certain new and useful Improvements in Permutation-Locks; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 My invention relates to a new and useful improvement in permutation-locks adapted for service upon trunks, closets, desks, and the like; and the novelty consists, essentially, in the construction and arrangement of parts, as 20 will be more fully hereinafter set forth, and specifically pointed out in the claims.

In this class of devices simplicity of construction, a minimum liability to get out of order, efficiency in service, and reliability and 25 compactness are of great importance.

To enable others to make and use my invention, I will now proceed to describe its construction and operation, reference being had to the accompanying drawings, in which—

30 Figure 1 represents a back plan view; Fig. 2, an enlarged sectional view taken on a line, xx , of Fig. 1; and Fig. 3, detail views of the permutation-disks and the disk carrying the arm and bolt.

35 Referring to the drawings, the letter A indicates the face-plate of ordinary ornamented form and material, and it is provided with a hasp-staple slot, a , at one side of which is a rigid guide, a' .

40 a^2 indicates a raised surface around the knob-shank aperture, from which extends backward, at right angles with the plane of the face, a sleeve, a^3 . Around this sleeve loosely operates a disk, B, having a tangential arm, B' , at 45 the outer end of which is the bolt B^2 , having a beveled surface. These parts B B' B² are formed in one piece, the bolt B² operating within the guide a' .

Pivoted upon the arm B', at c , is a lock-pawl, C, having a hook, c' , and a bearing, c^2 , for one 50 arm of a spring, C', which is properly secured to lugs or projections a^4 upon the face-plate. The hook portion c' is adapted to engage in the recesses d in interchangeable combination-disks D, which may be two or more in number, and operate loosely, but snugly, around the sleeve a^3 when the said recesses d are opposite each other. These recesses have abrupt sides, and the lock-pawl can only be released therefrom as it is forced out by the operating-disk, 60 which will hereinafter be described.

Each of the disks D has, at equal annular lines from the peripheries, pins d' driven entirely through the disk and projecting upon each side and differentially arranged with regard to the locking-recess d upon each disk. For instance, taking the recess as a basis and turning toward the left, the pins upon one disk may be placed at one-seventh of the circumference, and upon another disk at one-eighth, 70 and so on, care being taken not to place the pins opposite from the recesses d . By this construction the disks may be reversed or interchanged at will, and each change of position or location will change the combination. 75 As shown and described, there are but two of the disks D; but it is evident that more may be used if desired, or as many as the sleeve a^3 will hold. These disks D must be held into a desired set position by friction, and to this end 80 I provide a series of friction spring-fingers, e e , extending from a body, E, and formed of one piece of metal, the body being clamped tightly within a slot, e' , in a split projection or lug, E', upon the arm B'. 85

It is important, where springs are formed of very thin spring-steel, to avoid unnecessary friction, which friction tends to weaken the spring, and, in delicate complications, to destroy the efficacy of the parts. To avoid this 90 I construct and arrange the parts specified in such a manner relatively to each other that all manipulations of the bolt when the combination is "on" serves to move knob-shank, bolt, pawl, disks, and the fingered spring together, 95 and the only friction between the parts is con-

9
fined to a very limited space between the pawl C and spring C'; hence the advantage of securing the fingered spring E to the bolt-arm B'. H indicates the operating-disk, and it is provided with a recess, h, having one abrupt side and an incline, h', running from the bottom of the recess to the periphery. At a uniform distance from the common center of this disk is secured a circle of pins, h², of any desired number, of sufficient distance apart to admit between each pair of pins a spring-arm, I, having an open slot, i, which, when in position, embraces a slotted rectangular portion, i', of the knob-shank, and it may be readily changed to any position at will by springing the arm over the pins h², each change forming a separate combination.

K indicates the knob-shank; K', the outer disk, having the peripheral figures; and K², the knob. L indicates the hasp-body, having bearings l of semi-cylindrical form, to receive the journals m of the hasp-tongue M, at the free end of which is the hasp-staple m'. Rigidly secured to the hasp-body L, at o, is a flat spring, O, the free end o' of which bears against the back surface of the tongue, to throw it out of the slot a in the face-plate A as soon as the lock-bolt releases the staple m'.

30 Instead of having the series of pins upon the operating-disk, I may form a series of holes and place a single pin upon the spring-arm. It will be noticed that by placing the friction-springs upon the arm B' the disks, bolt, &c., 35 all move together, avoiding wear, which would result if the springs were fixed to the plate.

The operation of my invention is as follows: The knob-shank is passed through the proper aperture in the face-plate until the sleeve a³ is 40 projected through to its greatest extent and the figured disk lies close to the face. The combination-disks are then put in place and the friction-springs brought into action, after which the operating-disk is secured upon the 45 shank, and the spring-arm made to engage the rectangular end. As thus placed, by turning the arm in one direction the pin upon the back or under side engages the pin upon the second disk. The opposite pin upon that disk engages the next, and so on until the last disk 50

is engaged and the recess d therein brought in conjunction with the hook on the lock-pawl. Then reverse the revolution of the knob until, by a similar train of action, the next disk is brought into a similar relation, the springs 55 upon the arm B' holding each one by friction as soon as it is in position. When the last or operating disk is forced into position the lock-pawl springs into position and the bolt may be withdrawn.

60 It will be seen that the changes in the combination are almost innumerable.

Having thus fully described my invention, what I claim as new, and desire to secure by Letters Patent, is—

65 1. The spring-arm I, having rectangular open slot i, combined with the knob-shank having rectangular slotted portion i', and with the operating-disk H, having pins h², said arm serving the several functions of holding the 70 entire series of disks in place, of changing the combinations by being sprung over and between the pins h², and of being the operating means for manipulating the series of disks, as and for the purposes specified.

75 2. The combination of the disks D d d' and friction-springs, the operating-disk H, having annular pins h², the spring-arm I, the spring lock-pawl C, and lock-bolt B, all adapted to serve as and for the purposes set forth.

80 3. The disk B, arm B', and bolt B² made in one piece, in combination with the lock-pawl C, pivoted upon said arm, and the spring adapted to hold the lock-bolt in position, and also hold the spring lock-pawl into constant 85 contact with the disks, as specified.

85 4. The spring-body E, having spring-fingers e formed of one piece of metal, said body being clamped or held within a slot, e', in a lug, E', formed upon the bolt-arm B', in combination with disks D D, pawl C, and compound spring C', whereby the disks, bolt-arm, and pawl will move together when the bolt is retracted, as herein specified.

90 In testimony whereof I affix my signature in presence of two witnesses.

GEORGE M. HATHAWAY.
